US0D1077449S

(12) United States Design Patent (10) Patent No.: US D1,077,449 S
(45) Date of Patent: * Jun. 3, 2025

(54) SHOE

(71) Applicant: Birkenstock IP GmbH, Linz am Rhein (DE)

(72) Inventor: Barbara Storch, Vienna (AT)

(73) Assignee: Birkenstock IP GmbH, Linz am Rhein (DE)

() Term: 15 Years

(21) Appl. No.: 29/896,641

(22) Filed: Jul. 6, 2023

Related U.S. Application Data

(62) Division of application No. 35/515,518, filed on Oct. 10, 2022 (U.S. filing date under 35 U.S.C. 384), and having an international filing date of Oct. 10, 2022, now Pat. No. Des. 1,011,004.

CLAIM

The ornamental design for a shoe as shown and described.

DESCRIPTION

FIG. 1 is a front perspective view of the shoe showing my new design;

FIG. 2 is a bottom view thereof;

FIG. 3 is a rear view thereof;

FIG. 4 is a front view thereof;

FIG. 5 is a right side view thereof;

FIG. 6 is a left side view thereof; and,

FIG. 7 is a top view thereof.

The broken lines showing the sole of the shoe form no part of the claimed design.

1 Claim, 7 Drawing Sheets
